UNITED STATES PATENT OFFICE.

JAMES SAMUEL KING, OF LONDON, ENGLAND, ASSIGNOR OF ONE-HALF TO CHARLES KNIGHT & COMPANY, LIMITED, OF LONDON, ENGLAND.

BOOK WITH DETACHABLE LEAVES.

Application filed April 19, 1922. Serial No. 555,582.

To all whom it may concern:

Be it known that I, JAMES SAMUEL KING, a subject of the King of Great Britain, residing at 227-239 Tooley Street, London, 5 England, have invented a new and useful Improvement in Books with Detachable Leaves, of which the following is a specification.

The object of this invention is to provide 10 an improved means for securing the loose leaves of ledgers and the like of the type in which two or more straps secured to the inside of one half of the cover pass through the loose leaves and it may be also through 15 followers at the end and beginning of the leaves and into the interior of the other half of the cover where they are secured to a cross bar which is parallel to the hinge and is capable of slight movement towards and 20 away from the hinge.

According to this invention the cross bar has attached to it an actuating strap which passes towards the end of the cover remote from the hinge and has fastened to it a corrugated strip of metal or other suitable material while a similar corrugated strip is secured to the inside of the cover so that by 25 pressing the two corrugated strips together the strap can be secured in a number of 30 different positions each differing from the next by the distance between two successive corrugations. Preferably a flap or lid is hinged to the cover near its edge so that it can be folded down upon the strap and held 35 in position by pushing a tongue upon it under a transverse strip of metal fixed in the cover.

The invention is illustrated by the accompanying drawings, Figure 1 of which is a 40 perspective view of part of a loose leaf ledger constructed according to the invention part of the inside of the front cover being cut away to show the mechanism, while Figure 2 is a similar view showing the 45 flap or lid in its operative position.

A, A, A, are three straps which are secured to the inside of the back B of the cover; these pass through loose leaves C and through followers D into the interior of the 50 cover E within which they are secured to a cross bar F which is parallel to the hinge G and is capable of movement within the front

of the cover. Attached to the cross bar F is an actuating strap H which has secured to its underside a strip of corrugated metal 55 M. N is a similar corrugated strip secured to the inside of the cover. Hinged to the cover is a flap O in which can slide a tongue P. When the strap H has been pulled into the desired position it is pressed down so 60 that the ridges on the strip M enter the recesses of the strip N and the flap O is turned down into the position shown in Figure 2 and is locked in that position by pushing the tongue P beneath a strip of metal Q fixed in 65 the cover. Thus the bar F is locked.

What I claim is:—

1. In a book, the combination of two covers, a hinge uniting them, a cross bar slideable in one of the covers, a plurality of 70 straps one end of each being secured to the bar and the other end of each being secured to the other cover, a corrugated strip secured to the cross bar, a second corrugated strip secured to the cover first mentioned and 75 means whereby the two corrugated strips can be pressed together to fix the position of the cross bar.

2. In a book, the combination of two covers, a hinge uniting them, a cross bar slideable in one of the covers, a plurality of 80 straps one end of each being secured to the bar and the other end of each being secured to the other cover, an actuating strap secured to the bar, a corrugated strip on the strap, a 85 second corrugated strip secured to the cover first mentioned and means whereby the corrugated strip on the strap can be pressed against the corrugated strip on the cover.

3. In a book, the combination of two cov- 90 ers, a hinge uniting them, a cross bar slideable in one of the covers, a plurality of straps one end of each being secured to the bar and the other end of each being secured to the other cover, an actuating strap 95 secured to the bar, a corrugated strip on the strap, a second corrugated strip secured to the cover first mentioned, a flap hinged to the cover first mentioned and means for securing this flap in such a position that it 100 presses the two corrugated strips together.

4. In a book, the combination of two cov- ers, a hinge uniting them, a cross bar slideable in one of the covers, a plurality of

straps one end of each being secured to the bar and the other end of each being secured to the other cover, an actuating strap secured to the bar, a corrugated strip on the strap, a 5 second corrugated strip secured to the cover first mentioned, a flap hinged to the cover first mentioned and a slidable tongue by

which the flap can be secured in such a position that it presses the two corrugated strips together.

10

In testimony that I claim the foregoing as my invention I have signed my name this 5th day of April 1922.

JAMES SAMUEL KING.
